ELECTRICAL OUTLET DISTRIBUTION CABINET

Ralph W. Bickford, Napa, Calif., assignor to James L. Hall Co., Inc., San Francisco, Calif., a corporation of California

Filed June 11, 1965, Ser. No. 85,683

Term of patent 14 years

(Cl. D26—5)

FIG. 2

FIG. 1

FIG. 3

FIG. 4

FIG. 5

FIG. 6

FIG. 7

FIG. 8

FIG. 9

FIG. 10

FIG. 1 is a front elevational view of an electric outlet distribution cabinet showing my new design with a front movable portion in closed position;

FIG. 2 is one side view of FIG. 1;

FIG. 3 is the other side view of FIG. 1;

FIG. 4 is a back elevation view of FIG. 1;

FIG. 5 is a plan view of FIG. 1;

FIG. 6 is a bottom view of FIG. 1;

FIG. 7 is another side view of FIG. 1 in accordance with FIG. 2 but with a front movable portion thereof in an outwardly extending position;

FIG. 8 is a perspective front view of my invention as shown in FIG. 7;

FIG. 9 is a top view of FIG. 7; and

FIG. 10 is a bottom view of FIG. 7.

The dominant features of my new design are shown in solid lines in the drawing figures.

I claim:

The ornamental design for an electrical outlet distribution cabinet, as shown and described.
